CLAIM

The ornamental design for an electrical connector, as shown and described.

DESCRIPTION

FIG. 1 is a bottom, right side perspective view of an electrical connector of first embodiment, showing my new design;

FIG. 2 is a rear perspective view thereof;

FIG. 3 is a front elevation view thereof;

FIG. 4 is a rear elevation view thereof;

FIG. 5 is a top plan view thereof;

FIG. 6 is bottom plan view thereof;

FIG. 7 is a right side view thereof; and

FIG. 8 is a left side view thereof.

FIG. 9 is a bottom, right side perspective view of an electrical connector of second embodiment, showing my new design;

FIG. 10 is a rear perspective view thereof;

FIG. 11 is a front elevation view thereof;

FIG. 12 is a rear elevation view thereof;

(Continued)

FIG. 13 is a top plan view thereof;
FIG. 14 is a bottom plan view thereof;
FIG. 15 is a right side view thereof; and,
FIG. 16 is a left side view thereof.
The broken lines depict portions of the electrical connector
that form no part of the claimed design.

1 Claim, 16 Drawing Sheets
